UNITED STATES PATENT OFFICE.

ROSCOE H. ALDRICH, OF ALLENTOWN, PENNSYLVANIA, ASSIGNOR TO ALDRICH PUMP COMPANY, OF ALLENTOWN, PENNSYLVANIA, A CORPORATION OF PENNSYLVANIA.

REINFORCED PUMP-CASING.

1,327,512.

Specification of Letters Patent.

Patented Jan. 6, 1920.

Application filed March 22, 1919, Serial No. 284,245. Renewed November 14, 1919. Serial No. 338,114.

To all whom it may concern:

Be it known that I, ROSCOE H. ALDRICH, a citizen of the United States, and a resident of Allentown, in the county of Lehigh and 5 State of Pennsylvania, have invented a new and Improved Reinforced Pump-Casing, of which the following is a full, clear, and exact description.

The invention relates to pump casings 10 having a valve chamber provided with two or more entrance openings, and its object is to provide a new and improved cast metal pump casing which is reinforced at the bridge piece intermediate adjacent entrance 15 openings of the valve chamber. Another object is to provide a valve chamber of the proper area to accommodate two or more valves and at the same time permit of reducing the width of the valve chamber and 20 consequently that of the pump to a minimum.

With these and other objects in view, the invention consists of certain novel features of construction, as hereinafter shown and 25 described and then specifically pointed out in the claims.

A practical embodiment of the invention is represented in the accompanying drawings forming a part of this specification, in 30 which similar characters of reference indicate corresponding parts in all the views.

Figure 1 is a plan view of the reinforced pump casing;

Fig. 2 is a side elevation of the same;

Fig. 3 is a sectional side elevation of the same on the line 3—3 of Fig. 1; and

Fig. 4 is a cross section of the same on the line 4—4 of Fig. 1.

The pump casing 10 is made of cast iron 40 or of similar cast metal and is provided with a valve chamber 11 adapted to contain two or more valves (not shown). In order to give proper access to these valves the chamber 11 is provided in its top with 45 two openings 12 and 13 normally closed by suitable caps 14, 15 screwed or otherwise secured in position on the top of the chamber 11. The entrance openings 12 and 13 are separated by a transverse bridge piece 50 integral with the sides 21 and 22 of the casing 10, and in this bridge piece 20 is formed a transverse opening 23 into which fits and through which extends a bolt 24 preferably made of steel or other material 55 having a tensile strength considerably in excess of that of the material of which the

pump casing 10 is made. The head 25 of the bolt 24 abuts against the outer face of the side 21 while the nut 26 screwing on the other end of the bolt 24 abuts against the 60 outer face of the side 22, and this nut is screwed up sufficiently tight to place the bolt 24 under tension. It will be noticed that the bolt 24 greatly reinforces the bridge piece 20 as the bolt is of greater tensile 65 strength than the material removed by boring the hole 23, and as this bolt is held under tension it prevents the casing from unduly spreading and renders the casing sufficiently strong to readily withstand the 70 jars and other vibrations incident to the running of the pump by the seating or unseating of the valves thereof.

It will further be noticed that by providing the valve chamber 11 with a plurality 75 of valves arranged side by side a large pumping area is obtained without increasing the width of the pump casing and the pump casing is greatly reinforced by the use of the bolt 24, as above described.

Having thus described my invention, I claim as new and desire to secure by Letters Patent:—

1. A cast metal pump casing having a valve chamber provided with a plurality of 85 entrance openings, adjacent openings being separated by a bridge piece integral with the opposite walls of the casing and provided with a transverse opening extending through the said walls, and a reinforcing member of 90 greater tensile strength than the material of which the pump casing is made, the said reinforcing member fitting into and extending through the said opening and engaging the outer faces of the said walls of the cas- 95 ing, the said reinforcing member being under tension.

2. A cast metal pump casing having a valve chamber provided with a plurality of entrance openings, adjacent openings being separated by a bridge piece integral with the opposite walls of the casing and provided with a transverse opening extending through the said walls, and a bolt of 100 a material of greater tensile strength than that of which the said casing is made, the said bolt fitting into and extending through the said opening, the head and nut of the bolt engaging the outer faces of the said walls, and the said nut being screwed up to 105 hold the bolt under tension.

ROSCOE H. ALDRICH.
